TRUSS CONSTRUCTION

Colin Grant, Jackson, Mich.

Application December 30, 1938, Serial No. 248,392

6 Claims. (Cl. 128—105)

This invention relates to trusses and more particularly to the specific construction of the elements thereof.

The fitting of trusses has been somewhat difficult in the past due to the fact that a great many different designs and sizes were required for fitting different types of cases and different sized individuals. The present invention eliminates these difficulties by providing a truss which is not only readily adjustable to fit individuals of different sizes and to take care of different types of cases, but also makes possible the building up of a single or double truss or one which is of soft or spring construction from a few standard parts.

An object of the invention is to provide a truss adjustment which includes a running connection with a pad.

Another object of the invention is to provide a novel truss strap which is arranged to detachably receive a spring member to convert a soft truss into a spring truss, and vice versa.

A further object of the invention is to provide a novel truss strap structure.

Other objects reside in the details of construction of trusses which simplify their manufacture and facilitate and expedite the fitting thereof.

These and other objects will be apparent from the following specification when taken with the accompanying drawings, in which

Fig. 1 is a plan view of one form that the invention may take.

Fig. 2 is a side elevation of one of the back pads and associated straps,

Fig. 3 is a section on the line III—III of Fig. 2,

Fig. 4 is a side elevation of one of the active pads and its associated straps,

Fig. 5 is a section on the line V—V of Fig. 4,

Fig. 6 is a perspective view of one of the straps before it is stitched together showing details of construction,

Fig. 7 is an elevation of one of the straps showing its construction and the method of securing it to an active pad,

Fig. 8 is a perspective view from the front of another form that the invention may take,

Fig. 9 is a perspective view from the rear of the form disclosed in Fig. 8,

Fig. 10 is a side elevation of one active pad of the form of the invention disclosed in Fig. 8, and

Fig. 11 is a vertical section through the back pad and leg strap of the form of the invention disclosed in Fig. 8.

Referring particularly to the drawings, reference characters 1 and 2 indicate the active pads of the truss designed to exert the desired support and disposed against the front of the body of the wearer. The pads 1 and 2 each have rigidly connected thereto resilient straps 3, which are hereinafter described more in detail. The free ends 4 of the straps 3 are provided with a plurality of

holes 5, as shown particularly in Fig. 2, each hole 5 being surrounded by a metal grommet 6, as shown in Figs. 2 and 3.

At the rear of the truss are provided two back pads 7 permanently connected by a strap 8. Each pad 7 has a rear surface 9 of some durable flexible material, such as leather, and each surface 9 is cut to provide a band 10, shown particularly in Figs. 1 and 2, integrally connected at its ends and free from the pad at the intermediate portions thereof. In the center of each band 10 is an opening 11 surrounded by a grommet 12. Projecting outwardly from each pad 7 and beneath the opening 11 is a pin 13. The pin 13 is rigidly secured to a metal plate 14 within the pad 7, the plate 14 being secured to the pad 7 and the surface 9 by rivets 15. As shown particularly in Fig. 3, when the end 4 of a band 3 is passed between a pad 7 and its band 10, the pin 13 is disposed through one of the openings 5. As the band 10 is flexible it may be raised with respect to the pin 13 to lift the opening 11 from the pin 13 to permit any of the holes 5 to be disposed over the pin 13 so that an adjustable connection between the pad 7 and the adjacent strap 3 is provided. Also, the pin connections make possible a pivotal movement to permit the truss to change or adapt itself to various positions of the body of the wearer. Passage of the end 4 between the pad 7 and the band 10 is facilitated by constructing the pad 7 so that it is slightly yieldable in a direction perpendicular to the plane of the pad 7, thereby permitting the pad 7 and band 10 to be bowed to separate them.

The pads 1 and 2 comprise main body sections of some suitable construction provided with a rear cover plate 20 of metal secured to the pads by some suitable means, as screws 21. Each of the pads 1 and 2 has a pin 22 rigidly connected thereto and projecting normally from the rear face thereof. The pins 22 have adjacent the outer ends thereof annular grooves 23 for having sprung thereover a conventional releasable connector 24 provided internally with a spring ring 25 for disposition in the groove 23.

As shown particularly in Fig. 1, the releasable fastener 24 is positioned at one end of a connecting strap 26, which may be of pliable leather or the like. This fastener 24 is connected in a conventional manner to the pin 22 of the pad. The opposite end of the strap 26 is provided with a plurality of holes 27, as shown in Fig. 4. This end of the strap 26 projects through an opening 28 in a member 29 of some flexible material, such as leather, in which is mounted releasable fastener 24. As shown particularly in Figs. 1 and 4, one of the holes 27 in the strap 26 is disposed over the pin 22 projecting from the pad 2. The releasable fastener 24 in the member 29 is then moved over the pin 22

of the pad 2 and connected thereto in a conventional manner to secure the strap 26 against removal from the pin 22 projecting from the pad 2. It will be understood that any of the holes 27 in the strap 26 may be disposed over the pin 22 projecting from the pad 2 to adjust the distance between the pads 1 and 2. It should also be observed that the connection between the pads 1 and 2 and the strap 26 is pivotal as well as adjustable so that the pads 1 and 2 on the strap 26 may pivot respectively to each other to adjust the strap to the various positions which the body of the wearer might take.

The straps 3 are disclosed in detail in Figs. 6 and 7. In Fig. 6 is disclosed the method of making the strap itself without its spring reinforcing. The material from which the strap is made may be leather or some textile fabric, but it is preferred that the material be an artificial leather or the like having one side thereof finished in appearance and texture like leather and the reverse side being of napped fabric and soft. The strap is formed by rolling a strip laterally upon itself into a flat form until there have been formed two layers of approximately the same width and a third layer of approximately three-quarters of the width of the first two widths. The balance of the strip is then reversely rolled on itself to form substantially a closed loop. Stitching 36 is applied to the small substantially closed loop, extending through the entire strip, as shown in Fig. 7. The strip 35 is folded in such a manner that the under or napped side of the strip 35 is on the exterior of the larger fold and the finished or leather-like surface of the strip 35 is exposed on the smaller or upper fold. On either side of the upper fold are channels 31, into which are inserted spring wires 38, as shown in Figs. 3 and 7. The spring wires 38 are in the form of a loop having a closed end 39. An opening, not shown, is punched through one end of the strap 3 adjacent the end loop 39. In assembling the strap 3 on one of the pads 1 or 2, the cover plate 20 is removed and the end of the strap 3 having the opening is placed between the plate 20 and the pad. The plate 20 is then secured to the pad by the screws 21, one of them passing through the opening in the strap 3, thus firmly securing the strap 3 to the pad, not only by the clamping action of the cover plate 20 but also by the positive holding action of the screw 21. The spring reinforcing wires are freely slideable in the channels 31 in the strap 3 so that they may be removed from the strap 3 if a soft strap is desired rather than a spring one, or vice versa.

From the foregoing it will be clear that the truss which I have provided according to the present invention may be adjusted to fit the body of the wearer either by adjusting the length of the strap 26 between the pads 1 and 2 or by adjusting the length of the circumscribing straps 3. Furthermore, it will be clear that while I have disclosed a double truss, the truss may be converted into a single truss by the simple expedient of substituting for the one of the pads 1 or 2 and its strap 3 a soft strap. Thus, by a fitter having a predetermined set of standard parts, he can readily build up a soft or spring truss, a single or a double one, of any size that is desired, thereby not only making it unnecessary for him to have a large assortment of various forms and sizes of trusses but also making it possible to provide a more accurate fit than

is possible with premade trusses of standard sizes.

In Figs. 8, 9, 10 and 11 another form that the invention may take is disclosed. This form of the invention is particularly adaptable to soft trusses, that is, wherein the circumscribing belt is not provided with an internal spring for urging the active pads of the truss into contact with the body of the wearer. In Figs. 8 and 9 the truss comprises a circumscribing strap 45 of the same construction as the strap 3 disclosed in Figs. 6 and 7 except that the spring wires 38 are removed. On the front of the truss is an active pad 46 of some suitable construction and pivotally secured to the strap 45. Projecting outwardly from the pad 46 is a pin 47 about which the strap 45 is pivoted and arranged to receive pivotally a releasable fastener 48 of the same character as the fastener 24 disclosed particularly in Figs. 4 and 5. The releasable fastener 48 is disposed at one end of a connecting spring band 49. The band 49 is normally arcuate in configuration and connects the ends of the circumscribing strap 45. The function of the band 49 is to impart release to the circumscribing band 45 so that when the strap 45 is placed under tension, as due to some particular movement of the body of the wearer, the band 49 straightens out, thereby increasing the effective length of the strap 45. However, the effective length thereof is increased only a predetermined amount so that the desired pressure exerted by the pad 46 on the body of the wearer is maintained at a sufficient degree at all times.

The opposite end of the band 49 from that in which the releasable connector 48 is secured is provided with a plurality of openings 50 and passes between a pad 7 and its band 10 secured on the surface thereof, the pad 7 being of the same construction as the pad 7 disclosed in Figs. 1, 2 and 3. The pin 13 projecting outwardly from the pad 7 projects through any desired one of the openings 50 in the band 49.

The strap 45 has at the free end 51 opposite the end to which the pad 46 is attached a plurality of openings 52 longitudinally spaced. The end 51 is also disposed between the band 10 and the pad 7 with the pin 13 projecting through one of the openings 52. Thus, the strap 45 is adjustable as to length and is pivotally connected to the band 49.

Since the truss disclosed in Figs. 8 and 9 is of soft construction, it is necessary to have a strap 53 passing between the legs of the wearer to hold the pad 46 down in the position at which it is intended to bear. The strap 53 is of some conventional construction and is provided at the front end thereof with a releasable fastener 54 identical in construction to the fastener 24 disclosed in Figs. 4 and 5. The pad 46 is provided on the lower portion thereof with an outwardly extending pin 55 similar to the pin 47 for releasably and pivotally receiving the fastener 54. The opposite end of the strap 53 is provided with a plurality of openings 60 and is passed between the band 10 and a pad 7 disposed on the rear portion of the strap 45. The pin 13 of this pad 7 extends through one of the openings 60, pivotally and adjustably anchoring the rear end of the strap 53. The strap 45 also passes between the band 10 and the pad 7 at the rear of the truss and is provided adjacent the pad 7 with a plurality of openings 61, through one of which the pin of this pad projects. Thus, the pad 7

may be adjustably and pivotally positioned along the rear of the strap 45.

Also, at the rear of the strap 45 are disposed a plurality of longitudinally spaced openings 62 for the purpose of receiving another pad 7, if desired, as, for instance, when the truss is converted to a double truss by substituting for the front pad 7 an active pad similar to the pad 46. It will be understood that another leg strap similar to the strap 53 may be pivotally connected to such an additional active pad, if used.

It will be observed that the construction disclosed in Figs. 8 through 11 is adaptable to the same character of adjustment, fitting and remarking as the truss disclosed in Figs. 1 through 7. Also, as suggested above, the disclosed single truss may be readily converted to a double truss.

In both forms of the invention disclosed the pads 7 serve not only to provide pivotal points of contact for the truss to the body, but also provides a shield to hold the connections of the sections of the adjacent sections of the truss away from the body of the wearer, thereby eliminating any rubbing action that might otherwise occur at these points. The pivotal action of the pads 7 makes possible the continuous bearing of the pad 7 against the body without movement, while at the same time permitting relative pivotal movement of the sections of the truss adjoining the pad 7.

Having thus described my invention, what I desire to secure by Letters Patent and claim is:

1. In a device of the character described, a plurality of sections forming a circumscribing member having ends detachably secured together, the end of one of said sections overlapping the end of an adjacent section, a pad secured to the end of said adjacent section, a band on the surface of said pad attached at each end to said pad and being free in the middle, a pin projecting outwardly from said pad beneath said band into contiguity with said band, one of said overlapping ends having a plurality of openings therein spaced longitudinally thereof, said band being movable outwardly with respect to said pad, whereby said last named overlapping end may be projected between said pad and said band, said pin projecting through one of said openings to provide a pivotal connection between said overlapping end and said adjacent section, said plurality of openings being positioned to have any one of them received by said pin to provide an adjustable connection between said overlapping end and said adjacent section.

2. In a truss of the character described, a plurality of sections forming a circumscribing member having ends detachably secured together, one of said sections having a back pad connected at each end thereof, a band on the rear surface of each of said back pads attached at each end and being free in the middle, a pin projecting outwardly from each pad beneath its band, said sections adjacent each back pad having free ends overlapping the adjacent back pad and having a plurality of openings spaced longitudinally of the same adjacent the ends thereof, said ends projecting, respectively, between said pads and said bands, each end having the pin of the adjacent pad projecting through one of the openings therein to provide a pivotal connection between said pads and the adjacent sections, said plurality of openings providing adjustable connections, an active pad at the op-

posite end of each of said adjacent sections adapted to be disposed at the front of the body of the wearer, and means connecting said active pads.

3. A strap for use in spring and soft trusses and the like, comprising a strip of flexible sheet material rolled on itself in one direction and then rolled on itself in another direction to provide a base portion of a predetermined width and a top portion of a second predetermined but smaller width, stitching connecting said base and top portions, said stitching being spaced a predetermined distance inwardly from the edges of said top section to provide channels between said stitching and the edges of said top section, and resilient stiffening wires slidably disposed in said channels.

4. In a device of the character described, a circumscribing member having ends detachably secured together, an active pad on said member, an inactive pad disposed at the intersection of said ends, a band on the surface of said inactive pad attached at each end and free in the middle, and a pin projecting outwardly from said inactive pad beneath said band, said band being movable outwardly with respect to said pad, one of said intersecting ends having openings therein for the reception of said pin and being disposed between said inactive pad and said band, the other intersecting end being connected to said inactive pad, whereby said ends may be pivotally connected together and said inactive pad pivotally connected to at least one of said ends.

5. A device of the character described, a pair of sections having adjacent ends overlapping, a pad at the juncture of said sections, said pad having on one surface thereof a flexible band attached at each end to said pad and being free in the middle, a pin projecting outwardly from said pad beneath said band, said band due to its flexibility being movable outwardly with respect to said pad to permit the passage of one of said ends between said pad and said band, said last named end having a plurality of openings spaced longitudinally therein, said pin projecting freely through any one of said openings to provide a pivotal and adjustable connection between said last named end and said pad, and a connection between the other of said ends and said pad.

6. In a device of the character described, a body strap, an active pad secured to said body strap for bearing against a predetermined portion of the front of the body of the wearer, an inactive pad for engaging with the rear of the body of the wearer, a pin projecting from said inactive pad, said body strap having an opening therein, and said pin projecting through said opening to provide a pivotal connection between said body strap and said inactive pad, a leg strap secured adjacent one end thereof to said active pad, and having adjacent the other end thereof an opening, said pin projecting through said opening to provide a pivotal connection between said leg strap and said body strap and inactive pad at the rear of the body of the wearer, and a band on the surface of said inactive pad attached at each end to said inactive pad and being free in the middle, said body and leg straps passing between said inactive pad and said band, said band being over said pin for maintaining said body strap and leg strap on said pin.

COLIN GRANT.

CERTIFICATE OF CORRECTION.

Patent No. 2,284,143.

May 26, 1942.

COLIN GRANT.

It is hereby certified that error appears in the printed specification of the above numbered patent requiring correction as follows: Page 1, second column, line 51, for "pad" read --pad 1--; line 56, after the word "mounted" insert --the--; page 3, first column, line 14-15, for "remarking" read --remaking--; and that the said Letters Patent should be read with this correction therein that the same may conform to the record of the case in the Patent Office.

Signed and sealed this 21st day of July, A. D. 1942.

Henry Van Arsdale,
Acting Commissioner of Patents.
